Des. 93

Samuel Hanley (apptor to Durham, Sage & Gray, N.Y.
Letters Patent, Design No. 93, dated 10th October 1841)

The schedule referred to in these Letters Patent and making
part of the same.

To all to whom these presents shall come! Be it known that I,
Samuel Hanley of Troy, in the County of Rensselaer, and State of
New York have invented or produced a new design for stones, and that the
following is a full and exact description thereof, reference being had to the
accompanying drawings, in which figure 1 is a perspective view of the stone
showing the ornamental design of the front and side with the door open,
figure 2, is a similar view with the door closed, and the summer fix-
ture appended.

My invention consists in the ornamental embellishments of the
stone plates, being a pattern of foliated tracery consisting of wreaths
around the door and other parts of the stone usually plain, and an
intricate foliated ornament on the door of the stone composed of leaves
and branches as shown in the drawing a casting of the same being
filed in the patent office.

What I claim in this design and desire to secure by Letters
Patent is the production of the foliated ornaments described and illus-
trated as above set forth for ornamenting stone patterns.
